UNITED STATES PATENT OFFICE.

FENTON WRIGHT, OF FOUNTAIN GROVE, MISSOURI.

COIN-RECEPTACLE FOR SAVINGS-BANKS.

1,091,785.

Specification of Letters Patent. Patented Mar. 31, 1914.

Original application filed May 8, 1912, Serial No. 695,957. Divided and this application filed September 18, 1912. Serial No. 721,032.

To all whom it may concern:

Be it known that I, FENTON WRIGHT, citizen of the United States, residing at Fountain Grove, in the county of Linn and State of Missouri, have invented certain new and useful Improvements in Coin-Receptacles for Savings-Banks, of which the following is a specification.

My invention relates to savings banks and particularly to locking means therefor, this application being a division of my co-pending application Serial Number 695,957, filed May 8, 1912.

My above named application discloses a casing including clock mechanism and means for preventing the winding or setting of the clock or alarm except upon the deposit of a coin, while this present application covers the coin receptacle and locking means therefor.

One object of my invention is to provide a coin receptacle of relatively great strength and in which operative parts are entirely housed within the receptacle so that access cannot be gained thereto unless the receptacle be opened by means of a key or keys.

A further object is to provide a receptacle composed of telescoping sections and means for locking one of said sections in its retracted position within the other section.

A further object is to provide a receptacle consisting of two sections with a plurality of locking devices requiring a plurality of keys, access being had to one of the locking devices only after the other locking device has been operated.

A further object is to provide a coin receptacle consisting of telescoping sections, the outer section being formed with detents and the inner section with catches engageable over the detents and provide in connection therewith a key-actuated member connected with said catches, and a key-actuated plug or closing member which prevents access to the first named actuated member until removed.

Other objects will appear in the course of the following description.

My invention is illustrated in the accompanying drawing, wherein,

Figure 1 is a vertical section on the line 1—1 of Fig. 2; Fig. 2 is a vertical section on the line 2—2 of Fig. 1; Fig. 3 is a top plan view of the removable lower casing or section of the coin receptacle showing the man-

ner of operating the catches; Fig. 4 is a transverse section on the line 4—4 of Fig. 1; Fig. 5 is a fragmentary perspective view of the key employed in actuating the lock; and Fig. 6 is a section on the line 6—6 of Fig. 1 showing certain details of the lock structure; Fig. 7 is a like view to Fig. 6 but showing the parts in different position; Fig. 8 is a perspective view of the locking plug and key, the key being separated from the plug.

In my application above referred to I have illustrated and described a savings bank having two compartments, one of these compartments being for the reception of the coin and the other compartment containing a clock, an alarm and means whereby the deposition of a coin will act to remove certain barriers from in front of the clock winding, clock setting and alarm winding and setting arbors, this coin after it has actuated these instrumentalities eventually finding its way into the coin receptacle formed by the lower compartment.

Inasmuch as the mechanism above referred to is fully shown and described in my pending application I have deemed it unnecessary to illustrate this mechanism in the present case and only show therefore, the lower compartment or coin receptacle with the locking mechanism therefor.

The embodiment of my invention illustrated in the accompanying drawings includes an outer casing 10 preferably rectangular in shape and formed of metal, this casing being intersected at one end by a metallic plate 15, this plate 15 being provided with a slot 16 through which the deposited coin may drop into the receptacle.

The lower end of the casing 10 is closed by a removable casing 20 which forms the coin receptacle of the bank and which includes a bottom 21 and vertically extending walls 22. This removable casing is proportioned to fit closely within the main or outer casing, as best shown in Figs. 1 and 2 of the drawings and secured to the inner faces of the end walls of the removable casing, are leaf springs 23 which extend vertically of the casing and the upper ends of which terminate adjacent the upper ends of the walls of the inner casing in outwardly directed hooked terminals 24 having their outer upper portions beveled as shown at 25 for movement over the inner, lower beveled 110

faces 26 of the hooked terminals 27 carried by L-shaped arms 28 secured to the end portions of the lower plate 15. As best shown in Fig. 1, the upper portions of the end walls of the inner casing are slotted as at 29 to receive the hooks 27 when the removable casing is in place. As will be readily apparent, the insertion of the removable casing 20 in the lower end of the main casing 10 completely closes the main casing and the interengagement between the hooks 24 and 27 absolutely locks the removable casing against disengagement.

As a means for releasing the removable casing and removing the same, I have provided its bottom wall 21 with a centrally formed opening 30 and surrounding this opening and extending vertically upward within the removable casing, is a cylindrical casing 31 which is open at both ends and which terminates slightly below the upper end of the removable casing. Mounted in the upper end of this cylindrical casing 31, is the mechanism for releasing the hooks 24 from their engagement with the hooks 27. This mechanism includes a cylindrical body member 32 fitted closely within the upper end of the casing 31 and provided with a centrally formed longitudinal bore 33, counterbored at its upper end to form an annular shoulder 34 and provided adjacent its lower end with an annular groove 35 forming a shoulder 36. Positioned within the bore of this body member, is a post 37 having a shoulder 38 which engages with the shoulder 34 of the body member 32 and terminating at its upper end in a circular head 39 which bears upon the upper end of the casing 31. The post 37 is provided adjacent its upper end with an annular groove 40 and the body member 32 is supported in the upper end of the casing 31 by a split pin 41 which is passed through aligned perforations formed in the wall of the casing 31 and the wall of the body member 32 and the central portion of which seats in the groove 40 of the post 37. As will be seen, the passing of this pin through the body member and its casing serves to hold the body member against movement of any kind in the casing, while its seating in the groove of the post prevents the upward movement of the post, while at the same time permitting its free rotation in the body member. Threaded or otherwise secured in the upper face of the head 39, are diametrically disposed pivot pins 42 and secured by their inner ends to these pivot pins, are arms 43, the free ends of which are provided with downwardly directed hooked terminals 44 adapted to engage in openings formed in the laterally directed arms 45 of L-shaped plates 46 which are carried by the upper ends of the springs 23.

As will be apparent from the foregoing de-

scription, a rotation of the post 37 will act through the eccentrically positioned pivots 42 and the arms 43 to draw the upper ends of the springs 23 inwardly and so release their hooked terminals from the hooks 27 and permit the withdrawal of the removable casing. As a means for rotating the post 37, I have provided its lower end with a reduced extension 47 which, as best shown in Fig. 4, is formed with angular faces 75 adapted to seat in a correspondingly formed socket 48 in the terminal of a key shank 49 which, in operation, is passed upwardly through the opening 30 in the bottom of the casing 20. As best shown in Fig. 5 of the drawings, the free end of this key shank is provided with a longitudinally extending slot 50 having a laterally directed terminal 51 and, as will be seen by referring to Fig. 1 of the drawings, the body member 32 is provided with an inwardly directed pin 52 adapted to pass into the slot 50 of the key when the latter is applied to the reduced end of the post and to pass into the extension 51 of the key when the latter is turned 90 to release the hooks. By this means the turning of the key prevents its disengagement from the post and a downward pull upon the key will consequently draw the removable casing out of the main casing in 95 case of any binding or catching between their walls.

As a means for preventing any unauthorized removal of the casing 20 or coin receptacle, I preferably provide a plug lock 53 mounted in a cylindrical casing 54 proportioned to seat in and close the open lower end of the cylindrical casing 31. The lower end of this casing 54 is closed with the exception of a key receiving opening 55 and is provided at one side with a laterally directed extension 56 which seats in a correspondingly formed recess 57 in the bottom wall 21 of the removable casing and which prevents rotation of the lock casing within the casing 31 upon the turning of a key inserted into the lock through the opening 55. This plug lock consists primarily of a pivoted lock bar 58, the upper end of which is provided with a hooked terminal 59 adapted to engage the interiorly formed shoulder 36 of the body member 32, while the lower end bears against the tumblers 60. The lever 58 is pivotally mounted upon a pin 61 which passes through spaced shoulders 62 formed upon the inner wall of the lock casing and is normally held in operative position by means of a helical spring 63 which bears between the lock casing and the rear face of the lever 58. This spring is held against disengagement by a pin 64 which is secured by one end to the lock casing and the other end of which passes through a perforated plate 65 movable over the back face of the lever 58 and through a slot 66 formed in the 130

lever. When this plug lock is applied all access to the coin receptacle of the bank, by any one not having the proper key, is prevented and the provision of this auxiliary lock therefore prevents the necessity of the owner carrying around the key 49 previously described, which must, of necessity, be comparatively large. It also serves as an added lock as it is practically an absolute necessity to have both keys to open the bank, the pin 52 not only performing the function previously described, but also preventing the application of any ordinary form of socket key.

15 When the bank or coin receptacle is to be opened for the removal of the coins contained in the coin receptacle, the proper key is inserted through the opening 55 and turned to swing the tumblers 60 and thus activate the locking bar 58 to free it from the shoulder 36. When this occurs the plug lock 53 may be drawn from the end of the casing 31, the key 49 is then inserted in the end of the casing and engaged with the reduced 25 terminal 47 of the post 37 and with the pin 52 when the key is turned. When the key is turned it retracts the head 39 and causes the arm 43 to release the catches or hooks 24. Inasmuch as the key is at this time engaged with the pin 52, it will be obvious 30 that the inner casing or coin receptacle may be removed by the pulling upon the key which is held from disengagement by the pin 52.

35 When the coins have been removed, the coin receptacle or removable section of the casing may be replaced, the hooks 24 automatically engaging with the detents 27 to lock the removable section in place, after 40 which the plug lock is again applied to close the opening in the end of the removable section, and the key turned so as to lock the tumbler and permit the spring 64 to throw the locking member 58 over so that the head 45 59 will engage over the flange 36 through locking the plug lock in place.

It will be seen that in the mechanism as above described, all of the locking parts except the face plate of the plug lock are 50 entirely inclosed within the coin receptacle and it will be further seen that access cannot be made to the inner lock formed by the post 27 and the catches 24 until the outer lock has been actuated and the plug formed 55 by the barrel 54 removed. It is to be further noted in this connection that the pin 52 not only acts as an additional ward, preventing the operation of the post 47 except by a special key, but that it acts as 60 means whereby the key 49 may be used to withdraw the inner section of the coin receptacle from its telescopic engagement with the outer section.

The barrel of the plug lock 53 has its inner end cut away at an inclination so as to

70 permit the various parts carried in the interior of the plug lock to be readily assembled and put in position. The barrel is, however, elongated on one side so as to secure as much bearing as possible upon the tubular member 31 and also provide for the support of the pin 66.

75 It will be seen that any effort to withdraw the plug lock barrel from the casing section when the member 58 is in engagement with the flange 36 is resisted by the engagements of the tubular member 32 with the post 37 and with the tubular member 31, this tubular member 31 being formed preferably integral with the casing section. It would be 80 an approximately difficult matter to insert an implement around the end of the plug barrel and still more difficult to withdraw the plug barrel against the resiliency of the tubular member 31 which extends in line 85 with the force which would have to be applied to remove the barrel.

Having described the invention what is claimed is:

1. A coin bank including a casing section 90 having a coin slot, a second casing section insertible into one end of the first casing section and forming a closure therefor, interengaging hooks carried by said sections and arranged to automatically lock the two together, a cylindrical casing extending into the removable casing section, means carried by the cylindrical casing and operable by a key for releasing said hooks, and a plug lock 95 normally closing the outer end of said cylindrical casing. 100

2. A coin receptacle including telescoping sections, catches mounted on one of said sections and detachably engaging the other section, a key actuated member rotatably mounted in one of said sections and operatively engaging said catches, and a key actuated plug removable through the same section and disposed in alignment with the rotatable member and having locking engagement with said section. 110

3. A coin receptacle including telescopic sections, each of said sections being closed at one end and open at the other, one of said sections having a plug opening in its end, 115 catches carried by the last named section and detachably engaging the other section, a key actuated rotatable member mounted in the said section in alignment with said plug opening and operatively connected to said catches, a plug normally closing said plug opening but removable therefrom and key actuated locking means normally holding the said plug in place. 120

4. A coin receptacle including telescopic sections, each open at one end and closed at the other, catches mounted on one section and detachably engaging the other section, a tubular member mounted in said catch carrying section and opening through the 130

end thereof, a tubular sleeve mounted in the tubular member, a post rotatably mounted in the sleeve and having a key shank, means operatively connecting the rotatable post with said catches whereby the latter may be withdrawn upon the rotation of the former, a plug fitting the open end of the tubular member and closing the end of the section, and a key actuated latch disposed within

5

10 said plug and engageable with the sleeve to normally lock the plug in position.

5. A coin receptacle including telescopic sections, each having an open end and a closed end, catches carried by one section 15 and operatively engaging the other section to lock the sections together, a tubular mem-

ber extending inward from the opening in the end of said first named section, a post rotatably mounted in the tubular member and operatively connected to said catches to withdraw the same when the post is rotated, said post having a key engaging shank, and a key engaging pin carried by the tubular member and projecting radially in front of said shank.

25

In testimony whereof I affix my signature in presence of two witnesses.
